UNITED STATES PATENT OFFICE.

FERDINAND ARNOLD LUDWIG DE GRUYTER, OF AMSTERDAM, HOLLAND.

APPARATUS FOR RAISING AND LOWERING BOATS.

SPECIFICATION forming part of Letters Patent No. 407,891, dated July 30, 1889.

Original application filed July 24, 1888, Serial No. 280,934. Divided and this application filed January 2, 1889, Serial No. 295,217. (No model.) Patented in England May 24, 1888, No. 7,631; in France June 25, 1888, No. 191,415; in Sweden July 2, 1888, No. 1,582; in Norway July 9, 1888, No. 1,028; in Belgium July 10, 1888, No. 82,514; in Italy September 30, 1888, XLVII, 119; in Spain October 2, 1888, No. 8,482; in Austria-Hungary October 26, 1888, No. 30,047, and in Canada November 2, 1888, No. 30,081.

To all whom it may concern:

Be it known that I, FERDINAND ARNOLD LUDWIG DE GRUYTER, a subject of the King of Holland, residing at Amsterdam, in the 5 Kingdom of Holland, have invented Improvements in Apparatus for Raising and Lowering Ships' Boats, (for which patents have been obtained in England, No. 7,631, May 24, 1888; France, No. 191,415, June 25, 1888; Austria-Hungary, No. 30,047, October 26, 1888, Sweden, No. 1,582, July 2, 1888; Norway, No. 1,028, July 9, 1888; Belgium, No. 82,514, July 10, 1888; Canada, No. 30,081, November 2, 1888; Spain, No. 8,482, October 2, 1888; Italy, Reg. A. W. 15 Vol. XLVII, No. 119, September 30, 1888,) of which the following is a specification.

This invention has reference to apparatus for raising and lowering ships' boats, the object being to enable a ship's boat, even when 20 equipped and manned, to be easily raised clear of the chocks or lowered onto them.

This application is filed as a division of my pending application for United States Patent filed July 24, 1888, Serial No. 280,934.

25 The present application is intended to claim the second form or species of apparatus hereinbefore mentioned, as subject-matter taken out of the other specification.

In order that the nature of the present invention may be readily understood, reference 30 is had to the accompany drawing, which illustrates in elevation part of a davit with boat raising and lowering apparatus according to this invention suspended therefrom.

35 1 is part of a davit, or it may be a rod or bar connected therewith, formed with an eye 2, to which is hinged at 3 the upper block of lowering-tackle, that may be of the ordinary kind, and which comprises in the example 40 shown a pair of pulley-blocks 4.

45 5 is a rod formed with right-and-left-handed screw-threaded portions, upon which are fitted correspondingly screw-threaded nuts 6 6*. The upper nut 6 is connected by plates, or by a link or stirrup 7, to the frame of the lower tackle-block, the lower nut being similarly connected to the boat or to a hook or ring carried by it.

The screw-threaded rod 5 is provided with a

hand-lever 8, by turning which the lower nut 50 can be caused to approach or recede from the upper one to raise or lower the boat connected thereto.

With the arrangement described, by turning the hand-lever 8, and consequently the right-and-left-handed screw-threaded rod 5, a boat suspended to the lower nut 6* will be raised or lowered, according to the direction in which the screw is turned. Assuming a loaded boat to be on the chocks and each of two davits to 60 be fitted with apparatus of the kind hereinbefore described, if the two screw-threaded rods be turned simultaneously the boat can be raised from the chocks. Then it can be worked out, and afterward lowered over the 65 ship's side in the ordinary way.

What I claim is—

1. In an apparatus for raising and lowering ships' boats, the combination of lowering-tackle, and a rod formed with right-and-left-handed screws, correspondingly screw-threaded nuts fitted thereon, said rod being capable of rotation relatively to said nuts, one of said nuts being suspended from said lowering-tackle and the other adapted to be connected 75 to a boat to be raised and lowered, for the purpose specified.

2. In apparatus for raising and lowering ships' boats, the combination of a pair of pulley-blocks, a right-and-left-handed-screw-threaded rod, and correspondingly screw-threaded nuts, through which said rod can be caused to work, one of said nuts being connected to the lower pulley-block and the other adapted to be connected to a boat to be raised 85 and lowered, for the purpose specified.

3. In apparatus for raising and lowering ships' boats, the combination of a davit, lowering-tackle carried thereby, a rod formed with right-and-left-handed screw-threads, and correspondingly-formed nuts arranged thereon, one of which is suspended from said lowering-tackle and the other provided with means—such as bars 7—capable of being connected with a boat, said rod being capable of 90 rotation relatively to said nuts, substantially as described, for the purpose specified.

4. In apparatus for raising and lowering

ships' boats, the combination of a davit, pulley-blocks adapted to raise and lower a boat and suspended from said davit, and screw-gearing carried by said blocks and provided with means for connecting said gearing to a boat, said gearing comprising a right-and-left handed screw-threaded rod and correspondingly-formed nuts thereon, said rod being capable of rotation relatively to said nuts, substantially as described, for the purpose specified.

5. In apparatus for raising and lowering ships' boats, the combination of a davit, lowering-tackle suspended from said davit, a rod 15, formed with right-and-left-handed screw-

threads, a lever for rotating the said rod, and nuts 6 6*, adapted to work on said rod, but prevented from turning with reference thereto, one of said nuts being connected to said lowering-tackle and the other being adapted to be connected with a boat to be raised or lowered.

In testimony whereof I have signed my name to this specification in the presence of two subscribing witnesses.

FERDINAND ARNOLD LUDWIG DE GRUYTER.
